UNITED STATES PATENT OFFICE.

HERBERT R. TERRYBERRY, OF GRAND RAPIDS, MICHIGAN.

DESIGN FOR A BADGE.

50,470.

Specification for Design.

Patented Mar. 20, 1917.

Application filed January 29, 1917. Serial No. 145,336. Term of patent 3½ years.

To all whom it may concern:

Be it known that I, HERBERT R. TERRYBERRY, a citizen of the United States, residing at Grand Rapids, in the county of Kent and State of Michigan, have invented a new, original, and ornamental Design for Badges, of which the following is a specification, reference being had to the accompanying drawing, forming part thereof.

The figure is a face view of a badge, showing my new design.

I claim:

The ornamental design for a badge as shown.

HERBERT R. TERRYBERRY.

Witnesses:

CYRUS W. RICE,
GANSON TAGGART.
